CLAIM

The ornamental design for a construction safety handrail toeboard bracket, as shown and described.

DESCRIPTION

FIG. 1 is a top-front perspective view of the construction safety handrail toeboard bracket showing my new design;
FIG. 2 is a right side elevational view of the construction safety handrail toeboard bracket;
FIG. 3 is a left side elevational view of the construction safety handrail toeboard bracket;
FIG. 4 is a back elevational view of the construction safety handrail toeboard bracket;
FIG. 5 is a front elevational view of the construction safety handrail toeboard bracket;
FIG. 6 is a top plan view of the construction safety handrail toeboard bracket;
FIG. 7 is a bottom plan view of the construction safety handrail toeboard bracket; and,
FIG. 8 is a bottom-back perspective view of the construction safety handrail toeboard bracket showing my new design.
The retaining clips shown in broken lines depict environmental subject matter only and form no part of the claimed design.
